UNITED STATES PATENT OFFICE.

THOMAS GRISWOLD, JR., OF MIDLAND, MICHIGAN, ASSIGNOR TO THE DOW CHEMICAL COMPANY, OF MIDLAND, MICHIGAN, A CORPORATION OF MICHIGAN.

DRY CLEANING.

Application filed April 5, 1923. Serial No. 629,988.

To all whom it may concern:

Be it known that I, THOMAS GRISWOLD, Jr., a citizen of the United States, and a resident of Midland, county of Midland and 5 State of Michigan, have invented a new and useful Improvement in Dry Cleaning, of which the following is a specification, the principle of the invention being herein explained, and the best mode in which I have 10 contemplated applying that principle so as to distinguish it from other inventions.

The present improvements relate more particularly to certain developments in the method of cleaning and apparatus for use 15 in connection therewith that form the subject-matter of my co-pending application filed November 2, 1921, Ser. No. 512,242. Such method is characterized, among other things, by the step which consists in passing 20 a directed current of solvent through a definitely circumscribed portion of the fabric or like material from which a spot of oil or an equivalent soil mark requires to be removed and finds a special field of use 25 in the manufacture of knitted garments as in underwear factories where the current practice requires that garments on which spots are detected have to be thrown out and the spots washed with gasoline and soap 30 preparations, necessitating that they be subsequently dried and ironed. By my improved method I have rendered it possible to apply a solvent medium directly to the 35 damaged portion of the garments in such a manner as to eliminate the objectionable spot in a simple and expeditious manner so that the goods may be promptly returned to their original positions in the line of 40 progress of the material through the factory. At the same time the complete removal of the spot without objectionable "ringing" is insured.

One object of the present invention is the incorporation of a step in such method 45 whereby an air blast may be directed through the fabric, after treatment with such solvent, in order further to expedite the completion of the cleansing operation. Another object is to reduce the device or apparatus required to a more compact form suitable for installation on existing work benches, the principle of operation remaining substantially as described in such co-

pending application. Still another object is to provide an arrangement of tanks and 55 connections for supplying the solvent, as well as the compressed air, to a plurality of such devices installed on one or more floors of a manufacturing plant.

To the accomplishment of the foregoing 60 and related ends, the invention, then, consists of the means hereinafter fully described and particularly pointed out in the claims, the annexed drawings and the following description setting forth in detail 65 certain mechanism embodying the invention, such disclosed means constituting, however, but one of various mechanical forms in which the principle of the invention may 70 be used.

In said annexed drawings:—

Fig. 1 is a more or less diagrammatic representation of an installation of cleaning devices embodying my present improvements, such devices being shown as located 75 on different floors of a plant; Fig. 2 is a plan view of an individual cleaning device or apparatus embodying my present improvements; Fig. 3 is a vertical longitudinal section of such apparatus, the plane of 80 the section being indicated by the line 3—3, Fig. 2; Fig. 4 is a transverse vertical section of the same, the plane of such section being indicated by the lines 4—4, Figs. 2 and 3; Fig. 5 is partly a side elevation and 85 partly a vertical section of a control valve that forms a feature of such apparatus; Fig. 6 is a horizontal section through the portion of the device that directly co-operates with the material being cleaned, the 90 plane of such section being indicated by the line 6—6, Fig. 3; and Fig. 7 is a side elevation on a somewhat smaller scale than that of Figs. 2 et seq., showing in completely assembled form an individual device or apparatus with means for operating same.

Referring first to the more general illustration of my improved apparatus, as found in Figs. 1 and 7, the individual device comprising such apparatus will be seen to comprise a base 1 in the form of an inverted hollow shell that is adapted to be mounted upon a suitable table 2 or like support. The operative parts of the device, as shown in detail in the remaining figures, include as one principal element a hollow member or

pipe 5 of inverted U-shape, which may be referred to inclusively as a gooseneck, such member being attached to the base 1 by being oscillatorily mounted on a short 5 transverse tubular shaft 6 fixedly held in two bosses or standards 7 and 8 that rise above said base near the rear end thereof. The ends of said shaft 6 are closed, but it is provided with two lateral openings 9 and 10, the first of which communicates with the hollow interior of the gooseneck 5, while the other similarly communicates with a passage 11 in boss 8 to which is connected, by means of a coupling 12, one end 15 of a short pipe or duct 13.

It will be understood that, as clearly shown in Figs. 3 and 4, the rear end of said gooseneck, which is thus oscillatorily mounted on shaft 6 between bosses 7 and 8, 20 is permanently closed. The other or free end of said gooseneck, however, is open save for a disk valve 15 that is free to move outwardly from its seat against a cup member 16 that is secured to such end of the gooseneck by means of an annular cover member 17 formed at its lower edge with an encircling horizontal flange 18. A tension spring 19 assists in thus maintaining said valve normally in seated position against the cup 25 16 and the lower edge of the latter, which projects beyond the portion whereon said valve thus seats, forms a ring 20 that is adapted to press the material that is being treated against the peripheral portion of a 30 perforated working plate 21. Openings 22 in the lateral portion of cup 16 afford free communication between the interior thereof and the outer space defined by the cover 17.

Perforated working plate 21 is fixedly 40 mounted in the upper end of a cylindrical shell 25 of the cross-sectional form internally shown in Fig. 3, such shell being in turn reciprocably and to a limited extent oscillatorily mounted on the upper end of a 45 tubular boss 26 that rises from the bottom of an inverted casing 27, suitably supported in the base 1 with its upper end, which is normally open, directed upwardly and lying substantially in the plane of cup 16 and its 50 surrounding cover member 17 on the free end of the gooseneck when such end is depressed, as shown in the figure just referred to. As a matter of fact, such shell 25 is supported on boss 26 in the manner referred 55 to through the medium of an annular cushion 28 of suitable resilient material that will not be affected by the solvent used in the apparatus, such cushion ring 28 being interposed between a washer 29, that forms a 60 projecting flange on the upper end of the boss, and an annular flange 30 that projects inwardly from the cylindrical wall of said shell 25, the upper face of this last mentioned flange being beveled downwardly 65 and inwardly towards the central opening

therein which is aligned with the corresponding openings in cushion ring 28 and washer 29. A radial opening 31, it will be noted, extends through the wall of the shell 25 at a point immediately above said flange 70 30 or rather intersecting the upper beveled portion thereof by means of which opening communication is had between the interior of the shell and the surrounding annular space in casing 27. 75

The upwardly directed edge of said casing is beveled inwardly, and, seated in an encircling recess of rectangular cross-section located immediately below such edge, is another annular cushion 32 of material similar to that of cushion ring 28, such cushion being disposed to co-operate with the flange 18 on the cover member 17 that surrounds cup 16. 80

One end of a short pipe or duct 35 is laterally connected by means of an angular coupling 36 with the lower portion of casing 27 on one side thereof, the rear as shown in Fig. 3 (see also plan view, Fig. 2), the other end of such duct being connected with a valve chamber 37 that along with a companion valve chamber 38 is mounted in base 1 adjacent the aligned bosses 7 and 8 between which gooseneck 5 is oscillatorily mounted on pin 6. The duct 13, which, as hereinbefore described, is connected at one end by means of coupling 12 with the passage 11 in said boss 8 and thus with the hollow interior of said gooseneck, has its other end connected with such companion valve casing. The connection of each of such pipes 13 and 35 with the corresponding valve casings 38 and 37 lies above the seat in such casings against which the valves 38^a and 37^a, respectively, are held by means of springs 38^b and 37^b, respectively, thus closing communication between said ducts and the ducts 40 and 41 that lead to the respective lower portions of said valve casings. 90 The valves 37^a and 38^a are formed with stems 37^c and 38^c that project above the upper ends of the respective casings in position to be engaged by the oppositely extending arms of a rocker 42 oscillatorily mounted on a bracket 43 located between the valve casings and provided with a handle 44 for convenience in operation. From the foregoing construction it will be seen that upon swinging said lever 44 in one direction, e. g. to the right, as shown in Fig. 5, valve 37^a will be depressed and duct 35 thus placed in communication with duct 40, while upon swinging said lever in the opposite direction, valve 38^a will be depressed and duct 13 placed in communication with duct 41. 100

The rear end of gooseneck 5 extends downwardly through a suitable opening 50 in the top of base 1 and has fixed thereto an angular depending arm 51, the free end 110 115 120 125 130

of which is connected by means of a link 52 with a foot pedal 53, the effect of which when depressed is to rock said gooseneck about its pivotal axis so as to cause its forward end with the cup 16 carried thereby to be depressed, as shown in full lines in Figs. 3 and 7. Normally, however, such free end of the gooseneck is raised into the position shown in dotted outline in said Fig. 7 by a tension spring 54 connected with the upper end of arm 51 and the front wall of base 1.

As shown in Fig. 3, a set-screw 55 in an arm 56 projecting forwardly from the lower end of gooseneck 5 is adapted to be adjusted to limit the spring action or lift of the gooseneck. It will also be noted that as a result of the way in which the shell 25 that carries working plate 21 is supported on the boss 26, viz., through the medium of cushion ring 28, such shell and plate are rendered self-centering when cup-ring 20 is thus forcibly pressed down on said plate. In other words, such plate will automatically adapt itself to the changing angle of such ring and so insure the uniform clamping of the fabric inserted between the two; while cushion ring 32 similarly insures a seal between the cup cover 17 and the upper edge of casing 27.

Duct 40 constitutes a solvent-supply line connected with any suitable source of supply, such as the one hereinafter described, while duct 41 constitutes an air-supply line, being connected with a suitable source of compressed air or equivalent pressure fluid. In addition to the foregoing ducts or lines, still another duct or line 57, leading to a suitable storage tank or the like, is connected with the hollow boss 26 that rises from the bottom of the casing 27, as hereinbefore described, and carries the shell 25 with its perforated working plate 21 (see Figs. 2 to 6).

The operation of the apparatus may be conveniently described at this point. With the gooseneck 5 in its normal raised or open position, as shown in dotted outline in Fig. 7, the fabric is drawn across the upper beveled edge of casing 27 so as to substantially center the spot which it is desired to remove over the working plate 21. It will be observed that both hands of the operator are left free for this operation, following which by pressing down upon treadle 53 with his foot the operator depresses the free end of the gooseneck so as to clamp the fabric between the annular flange 18 and the cushion ring 32, the ring 20 of cup 16 being at the same time caused to clamp such material about a smaller concentric circle against the edge of shell 25, or in other words to the edge of the perforated working plate 21. The next step in the operation of the apparatus is to rock valve lever

44 to the right, as shown in Fig. 5, or to the rear, assuming the operator to be standing in front of the free end of the gooseneck, i. e., to the left and facing the base 1, as shown in Figs. 2, 3 and 7. The result of such actuation of the valve lever is to open valve 37^a, thereby admitting solvent from line 40 to duct 35 and thence to casing 27 where it wells up in the annular space surrounding boss 26 and shell 25 and overflows through the openings 22 in cup 16 on to the circular section of the material clamped by the ring 20 against the working plate 21. However, in thus passing upwardly in casing 27, the fresh or clean solvent it will be noted first encounters the annular portion of the material that lies between said ring 20 and flange 18, whereby the material is clamped on a larger circle against cushion ring 32. Accordingly, a barrier ring of the material is saturated with such clean solvent surrounding the spot before the solvent passes downwardly through the soiled portion of the material, and thence out through drain connection 57. It will be understood that the rate of flow of the solvent is suitably adjusted by means of a control valve in the supply line 40 so that the flow thereof through the apparatus, as just described, need be continued for only a brief interval in order to insure thorough cleansing of the spot in the material. Thereupon the valve handle is released, allowing valve 37^a to automatically close, and the handle is then pulled forwardly or to the left, as shown in Fig. 5, with the result that valve 38^a is opened and compressed air admitted from line 41 to duct 13 and thence to the hollow interior of the gooseneck 5 where the pressure overcomes the resistance of spring 19 and displaces valve 15 from its seat in the cup 16 in the forward end of the gooseneck. The air thence escapes through the clamped solvent wetted portion of the fabric violently displacing and ejecting through drain pipe 57 solvent retained in the fabric.

The valve 15 consists of a thin disk of suitable material and has as its function to prevent the solvent during the first part of the operation from rising into the gooseneck, compelling it instead to follow the path previously described.

The flow of air is continued long enough to substantially free the fabric from excess solvent retained by it whereupon the operation may be considered complete and valve 38 allowed to automatically close by again releasing lever 44. In order to remove the fabric that has been operated upon, the treadle 53 is released and spring 54 thereupon automatically raises the gooseneck, thus restoring the apparatus to its initial position ready for another operation. It may be noted at this point that the port 31 in shell 25 permits solvent

trapped in the annular space between shell 25 and casing 27 to drain into boss 26 or to be ejected therein by air from the goose-neck.

5 While, as indicated, the operation of the apparatus as just described is not dependent upon any particular source of supply for either the solvent or compressed air employed in such operation, I have shown in 10 Fig. 1 a special arrangement or system designed for thus supplying solvent and compressed air to a plurality of machines in a factory and also for collecting the residual solvent that drains from such machines in 15 incidental to each cleaning operation. In said Figure, two devices are shown located on separate floors of a building together with pipe lines 40, 41 and 57 which are connected therewith respectively, as here- 20 inbefore described in detail.

Two solvent tanks are provided, an upper tank 60 located above the level of the highest device in the system, and a lower tank 61 located below the lowest such device. Solvent delivered in shipping containers 62 may be introduced into the system by air pressure using the pipe connections shown in dotted lines. There is also provided a clean air tank 63 which is designed to be supplied with air under proper pressure from the house main 64, such air first passing through a reducing valve 65 and filter 66 adapted to remove any foreign matter which might soil or spot the fabric being treated. The solvent is supplied from the upper solvent tank 60 through a main line 67 wherewith the several ducts 40 are connected, while the solvent that is drained away through the several ducts 57 is collected in a companion main 68 and carried to the lower tank 61. An air vent permits relieving air pressure after elevating solvent and the displacement of air as necessitated by changing 45 volume of solvent in tanks. The air collected through said ducts 57 from the several devices is vented either through the roof or otherwise. Line 67 is so connected with lower tank 61 or drum 62, that air pressure from an extension 64^a of the house main may be used to elevate solvent from such tank or drum to the upper tank.

If desired, the used solvent may be conducted to a still in which it is vaporized and 55 the vapor carried to a condenser located above the upper solvent tank. By re-distilling the solvent each time it is used, all oil or dirt extracted is left behind in the still and only pure solvent supplied to the upper solvent tank and thence to the devices.

Both the foregoing methods avoid the use 60 of pumps or other moving machinery and are applicable to installations in which a number of spotting machines are used. For 65 small installations, however, it will prob-

ably be more economical to carry the solvent by hand from the lower to the upper tank.

Other modes of applying the principle 70 of my invention may be employed instead of the one explained, change being made as regards the means and the steps herein disclosed, provided those stated by any of the following claims or their equivalents be employed.

I therefore particularly point out and distinctly claim as my invention:—

1. In a method of removing a spot from a fabric or like material, the steps which consist in passing a directed current of solvent through a definitely circumscribed portion of such material, including the spot, and then passing through such portion a gaseous fluid adapted to displace retained solvent.

2. In a method of removing a spot from a fabric or like material, the steps which consist in passing a directed current of solvent through a definitely circumscribed portion of such material, including the spot, and then passing through such portion in the same direction a gaseous fluid adapted to displace retained solvent.

3. In a method of removing a spot from a fabric or like material, the steps which consist in passing a directed current of solvent through a portion of such material immediately surrounding but not including the spot and then through the portion of such material including such spot, and thereupon passing through such portions a gaseous fluid adapted to displace retained solvent.

4. In a method of removing a spot from a fabric or like material, the steps which consist in passing a directed current of solvent through a portion of such material immediately surrounding but not including the spot and then through the portion of such material including such spot, and thereupon passing through such portions in the same order a gaseous fluid adapted to displace retained solvent.

5. In a method of removing a spot from a fabric or like material, the steps which consist in sealing off a definitely circumscribed portion of such material, including the spot, also sealing off another portion of such material immediately surrounding such first portion, and then passing a current of solvent through such surrounding and central portions in the order named.

6. In a method of removing a spot from a fabric or like material, the steps which consists in sealing off a definitely circumscribed portion of such material, including the spot, also sealing off another portion of such material immediately surrounding such first portion, passing a current of solvent through such surrounding and central portions in the order named, and then passing

through such portions a gaseous fluid adapted to displace retained solvent.

7. In a method of removing a spot from a fabric or like material, the steps which consist in sealing off a definitely circumscribed portion of such material, including the spot, also sealing off another portion of such material immediately surrounding such first portion, passing a current of solvent through such surrounding and central portions in the order named, and then passing through such portions in the same order a gaseous fluid adapted to displace retained solvent.

15 8. In an apparatus of the character described, the combination of separable members adapted to clamp therebetween a circumscribed area of a piece of fabric or like permeable material, said members being chambered to permit the circulation of a fluid through the enclosed area of such material, and connections to said members adapted respectively to supply a solvent and a gaseous medium adapted to displace solvent retained by such material.

30 9. In an apparatus of the character described, the combination of separable members adapted to clamp therebetween a circumscribed area of a piece of fabric or like permeable material, said members being chambered to permit the circulation of a fluid through the enclosed area of such material, connections to said members adapted respectively to supply a solvent and a gaseous medium adapted to displace solvent retained by such material, and a drain connection.

40 10. In an apparatus of the character described, the combination of separable members adapted to clamp therebetween a circumscribed area of a piece of fabric or like permeable material, said members being chambered to permit the circulation of a fluid through the enclosed area of such material, connections to said members adapted respectively to supply a solvent and a gaseous medium adapted to displace solvent retained by such material, and alternatively operable valves controlling said connections.

50 11. In an apparatus of the character described, the combination of separable members adapted to clamp therebetween a circumscribed area of a piece of fabric or like permeable material, said members being chambered to permit the circulation of a fluid through the enclosed area of such material, connections to said members adapted respectively to supply a solvent and a gaseous medium adapted to displace solvent retained by such material, alternatively operable valves controlling said connections, and a drain connection.

60 12. In an apparatus of the character described, the combination of a cylindrical shell, a casing surrounding said shell and

leaving an annular space therebetween, and a relatively movable cup-member provided with rings adapted to co-operate with the ends of said shell and casing respectively to clamp a piece of fabric or like material thereagainst.

70 13. In an apparatus of the character described, the combination of a cylindrical shell, a casing surrounding said shell and leaving an annular space therebetween, and a relatively movable cup-member provided with rings adapted to co-operate with the ends of said shell and casing respectively to clamp a piece of fabric or like material thereagainst, the foregoing parts being self-centering.

75 14. In an apparatus of the character described, the combination of a cylindrical shell, a cushion ring supporting said shell, a casing surrounding said shell and leaving an annular space therebetween, a cushion ring fitted to the end of said casing, and a relatively movable cup-member provided with rings adapted to co-operate with the ends of said shell and casing respectively to clamp a piece of fabric or like material thereagainst.

80 15. In an apparatus of the character described, the combination of a cylindrical shell, a cushion ring supporting said shell, a perforated plate carried by said shell, a casing surrounding said shell and leaving an annular space therebetween, a cushion ring fitted to the end of said casing, and a relatively movable cup-member provided with rings adapted to co-operate with the ends of said shell and casing respectively to clamp a piece of fabric or like material thereagainst.

85 16. In an apparatus of the character described, the combination of a cylindrical shell, a casing surrounding said shell and leaving an annular space therebetween, a relatively movable hollow member provided with rings adapted to co-operate with the ends of said shell and casing respectively to clamp a piece of fabric or like material thereagainst, a connection for supplying solvent to said casing, and a connection for supplying to said hollow member a pressure fluid adapted to displace retained solvent from such material.

90 115 17. In an apparatus of the character described, the combination of a cylindrical shell, a casing surrounding said shell and leaving an annular space therebetween, a relatively movable hollow member provided with rings adapted to co-operate with the ends of said shell and casing respectively to clamp a piece of fabric or like material thereagainst, a connection for supplying solvent to said casing, a connection for supplying to said hollow member a pressure fluid adapted to displace retained solvent from such material, and alternatively operable valves controlling said connections.

120 125 130 18. In an apparatus of the character de-

scribed, the combination of a cylindrical shell, a casing surrounding said shell and leaving an annular space therebetween, a relatively movable hollow member provided with rings adapted to co-operate with the ends of said shell and casing respectively to clamp a piece of fabric or like material thereagainst, a connection for supplying solvent to said casing, a connection for draining said shell, and a connection for supplying to said hollow member a pressure fluid adapted to displace any absorbed solvent from such material.

Signed by me this 30 day of March, 1923.

THOMAS GRISWOLD, JR.
